UNITED STATES PATENT OFFICE.

ELIE W. LABOMBARDE, OF NASHUA, NEW HAMPSHIRE.

PAPER BOX.

1,365,251.

Specification of Letters Patent. Patented Jan. 11, 1921.

Application filed April 27, 1917. Serial No. 164,880.

To all whom it may concern:

Be it known that I, ELIE W. LABOMBARDE, of Nashua, in the county of Hillsborough and State of New Hampshire, have invented 5 certain new and useful Improvements in Paper Boxes, of which the following is a specification.

This invention relates to paper boxes of the type which can be shipped flat to customers and then set up for use by the latter, as needed.

One of the objects of this invention is to provide boxes of this type which, when set up for use, will closely resemble boxes which 15 are furnished to customers already set up and glued, without involving so much expense or requiring the space necessary in the manufacture, shipping and storing of such previously set up and glued boxes.

Another object is to provide a structure 20 of box having a cover section, with improved means whereby the cover may be readily moved to closing position and will be firmly held closed.

With these and further objects in view my 25 invention consists in the box or blank substantially as hereinafter described and claimed.

Of the accompanying drawings:

Figure 1 is a plan view of a blank made 30 according to one embodiment of my invention.

Fig. 2 represents a section on line 2—2 of Fig. 1.

Fig. 3 is a view similar to Fig. 2 but illustrating one of the preliminary steps of converting the blank to box form.

Figs. 4 and 5 are detail perspective views 40 to illustrate successive folding or setting-up steps. The loose ornamental flaps are omitted from these figures, to enable other parts to be clearly shown.

Figs. 6 and 7 are sectional views of the 45 set-up box, with the cover open and closed respectively.

Referring first to Figs. 1 and 2 the blank is cut and creased to provide a rectangular portion 12 which is to form the bottom of the box, two side wall sections 13, 14, one of 50 which, when the box is to have an integral cover, has an extension 15 provided with tucking flaps 16, 17, 18. The section 13

has an extension 131 the purpose of which will be hereinafter described.

Each end wall portion of the blank comprises sections 19, 20, extending from the central portion 12, there being two parallel creased lines between said sections 19, 20, for a purpose hereinafter described.

Each section 20 is cut in from its outer 60 edge to provide a locking tongue 21 at the base of which are two short slits 22 extending toward each other.

A flap 23 extends from each end of the side wall section 13, and a flap 24 extends 65 from each end of the side wall section 14. The flaps 24 are longer than the flaps 23 and the outer ends of these flaps 23, 24, are illustrated as cut off at an angle of 45 degrees, as at 25, 26, respectively, for purposes 70 presently described.

Each flap 24 is provided with an opening 75 from which short slits 28 extend in opposite directions, to coöperate with the locking tongue 21.

The wall section 13 is formed with a long slit 29.

Boxes of high grade employed for such goods as candy usually have means inside the box cover for overlying the contents, 80 said means consisting of one or more flaps of thin, ornamental material, called "lace-paper," each flap being secured at one edge to an upper portion of a side wall of the box. I attach such flaps to the blank before it is set up, by machinery which feeds strips of the lace paper and cuts off the proper lengths and adhesively connects them to the portions of the blanks which become the inner upper portions of two of the side 85 walls of the box when the latter is set up. One of these strips is shown at 30, its inner edge being secured to the section 14 near the crease line which forms the hinge for cover section 15. The other strip 31 has one 90 edge secured to the opposite surface of the blank and preferably to the section 131. The 95 edge secured to the opposite surface of the blank and preferably to the section 131.

With the construction illustrated, the first step of converting or setting up the blank to box form may be to fold the section 131 100 against the inner face of section 13. This, as shown in Fig. 3 swings the "lace paper" flap 31 so that its free edge extends opposite to the free edge of the other "lace paper"

flap 30. This folding of flap 131 may be effected later however, after the end wall portions have been folded as shown in Figs. 4 and 5 in which the section 131 is shown as not folded. As a matter of fact, there is no essential difference in the final result whether the section 131 is folded first or later. Fig. 3 shows it as a first fold, mainly to illustrate the position of strip 31 relatively to strip 30.

After the wall sections 13, 14 are turned up to the Fig. 4 position the flaps 23, 24 are turned toward each other, their inclined edges 25, 26, just meeting, edge to edge. As they do not overlap, the end walls of the box are less cumbersome than in boxes which do have overlapping flaps at such points. Each flap 24 is longer than its companion flap 23 and therefore has greater area for the opening 27 and slits 28 and permits wider and consequently stronger locking devices 21, 27, 28 than would be the case if the two flaps 23, 24, were of equal length, whether the outer edges of said flaps were inclined or not. At the same time the edge of flap 23, when in set-up position, is amply long to be engaged by the end wall sections when they are over-folded as presently described, to be held down and, in turn, hold down the flap 24.

After the flaps 23, 24, are bent to the Fig. 4 position, each section 19 is swung up against the outer surfaces of said flaps and then each section 20 is carried over inside so that the two sections 19, 20, inclose the flaps 23, 24. During the last of the movement of each section 20, its tongue 21 is pushed through opening 27 until the shoulders resulting from the formation of slits 22 interlock with the shoulders which result from the formation of slits 28. This engagement or interlocking is so positive that it is impossible to unlock and unfold the box without tearing the inter-engaging parts. The fact that the flaps 24 are longer than flaps 23 results in the points where tongues 21 are interlocked with the openings 27 and slits 28 being nearer the center of each end of the folded box than would be the case if the flaps were of equal length. The reason for the double or parallel creases between the sections 19, 20, is to facilitate the end folding operation, including the pushing of the tongues to locked positions.

If the section 131 has not been preliminarily folded but is standing up as in Fig. 5, it is folded over inside as shown in Fig. 6. This section 131 not only strengthens the front wall of the box, but its ends form abutments for the front edges of sections 20 and prevent said sections from bulging in. The rear portions of sections 20 can not bulge in because of the locked tongues 21.

The thin paper strips 30, 31, are omitted from Figs. 4 and 5 in the interest of clear-

ness. It will be readily understood that when such strips are located as in Figs. 1, 2 and 3 and the blank has been folded or set up as described, said strips will extend toward each other as shown in Fig. 6, to overlie goods in the box. When the cover is closed to the Fig. 7 position, the flaps 17, 18, are tucked inside the tops of the end walls and the flap 16 is slipped through the slit 29, the lower edge of said flap 16 being then confined between the sections 13, 131, and firmly held thereby.

Owing to the fact that the flaps 23 are continuations of section 13 in the sense of being integral therewith, the slit 29 in said section 13 can be very long without tearing out at its ends. That is, the slit 29 can extend nearly if not quite to the corners of the box so as to receive a very long tucking flap 16 that will hold the cover down uniformly from end to end. Any extension of the slit 29 due to tearing at its ends would be arrested at the corner or corners of the box because the tear would not extend into a flap 23 which is then at a right angle to wall section 13. The flaps 23 can not get out of this angular position because they are held between the double wall sections 19, 20. And the latter are held folded because of the interlocking at 21, 27, and also by the ends of section 131 when the latter is present as described, said ends forming stops or abutments for the front edges of sections 20.

I do not limit myself to the employment of the section 131. If that section is omitted, the thin flap 31 will then be attached to the section 13 near its edge and just away from the slit 29.

The boxes or blanks may be made in any size and of any proportions. And it is to be understood that the terms "side" and "end" are employed only for convenience of description, and are not to be understood as limitations meaning that the box is elongated, or if elongated, which dimension is the greatest.

Having now described my invention, I claim:

1. A blank creased to be folded to form the bottom and wall portions of a box, said blank having a pair of flaps in spaced parallel relationship, the marginal portions of said flaps being secured to opposite surfaces of those portions of two wall sections in such locations as to be at the top when the blank is converted to box form, said flaps being of relatively thin material and free to extend loosely toward each other over the contents of the box.

2. A box blank comprising a central portion, a front wall section having a slit and end flaps, a rear wall section having a cover section and a tucking flap to engage said slit of the front wall section and having also end flaps longer than the end flaps of the

front wall section, and foldable end wall sections adapted to inclose said end flaps when the blank is converted to box form, the longer end flaps and the edge portions 5 of the foldable end wall sections having co-operating interlocking members, the end flaps of the front wall section extending

across the ends of the slit in said section whereby the slit is prevented from tearing beyond the corners when the blank is converted to box form. 10

In testimony whereof I have affixed my signature.

ELIE W. LABOMBARDE.
